UNITED STATES PATENT OFFICE

STANLEY L. MOODY, OF DES MOINES, AND WARREN M. LOUCKS, OF VALLEY JUNCTION,
IOWA

DESIGN FOR A COMBINATION TOBACCO ASH RECEPTACLE AND CIGARETTE SNUFFER

Application filed April 16, 1931. Serial No. 39,510. Term of patent 7 years.

To all whom it may concern:

Be it known that we, STANLEY L. MOODY and WARREN M. LOUCKS, citizens of the United States and residents of Des Moines, Polk county, Iowa, and Valley Junction, Polk county, Iowa, respectively, have invented a new, original, and ornamental Design for a Combination Tobacco Ash Receptacle and Cigarette Snuffer, of which the following is a specification, reference being had to the accompanying drawings, forming a part thereof.

Fig. 1 is a top plan view, and Fig. 2 is a side view of our combination tobacco ash receptacle and cigarette snuffer.

We claim:

The ornamental design for a combination tobacco ash receptacle and cigarette snuffer, as shown.

STANLEY L. MOODY.
WARREN M. LOUCKS.
